CLAIM

The ornamental design for a kitchen island with wine cooler, as shown and described.

DESCRIPTION

1. Kitchen island with wine cooler

1.1 : Perspective

1.2 : Front

1.3 : Back

1.4 : Left

1.5 : Right

1.6 : Top

1.7 : Bottom

1.8 : Perspective view with the door closed

1.9 : Perspective

1.10 : Front

1.11 : Back

1.12 : Left

1.13 : Right

1.14 : Top

1.15 : Bottom

1.16 : Perspective

1.17 : Front

1.18 : Back

1.19 : Left

1.20 : Right

1.21 : Top

1.22 : Bottom

(Continued)

The broken lines indicate portions of the article that form no part of the claimed design.

1 Claim, 22 Drawing Sheets
